PORTABLE ELECTRIC FOOD MIXER

Frederick G. J. Grise, New Braintree, Mass., assignor, by
mesne assignments, to Electric Spoon, Inc., West Brook-
field, Mass., a corporation of Massachusetts

Filed Oct. 9, 1961, Ser. No. 67,018

Term of patent 14 years

(Cl. D44—1)

FIG. 1 is a top perspective view of a portable electric food mixer showing my new design;

FIG. 2 is a bottom perspective view.

The essential features of the design are shown in full lines.

I claim:

The ornamental design for a portable electric food mixer, as shown and described.
